FIG. 6 is a top view of the athletic sandal upper of FIG. 1; and,
FIG. 7 is a bottom view of the athletic sandal upper of FIG. 1.

In FIGS. 1–7 the consistent length broken lines depict unclaimed environmental structure. The alternating-length

broken lines seen in FIGS. 1 and 4–6 depict the boundary of

the claimed design. The broken lines and the structures they

depict form no part of the claimed design.

The embodiment of the athletic sandal upper shown in FIGS.

1–7 is for a left foot. The embodiment of the athletic sandal

upper for a right foot is a mirror image of the embodiment

shown in FIGS. 1–7 about a sagittal plane of a human body.
